UNITED STATES PATENT OFFICE.

JACOB BENEDICT, OF GRAND RAPIDS, MICHIGAN, ASSIGNOR TO JULIAN M. WHEELER, WILLIAM GREEN, ABRAM B. KNOWLSON, JAMES S. COWIN, AND AARON L. SIBLEY, ALL OF SAME PLACE.

FOLDING TABLE.

SPECIFICATION forming part of Letters Patent No. 310,245, dated January 6, 1885.

Application filed October 23, 1883. (No model.)

To all whom it may concern:

Be it known that I, JACOB BENEDICT, a citizen of the United States, residing at Grand Rapids, in the county of Kent and State of Michigan, have invented a new and useful 5 Folding Table, of which the following is a specification, reference being had to the accompanying drawings.

This invention relates to lock-hinges for the 10 legs of tables, benches, and the like; and it has for its object to provide a device which shall possess superior advantages in point of simplicity, durability, and general efficiency.

To this end it consists in certain improvements in the construction of the same, which will be hereinafter fully described, and particularly pointed out in the claim.

In the drawings hereto annexed, Figure 1 is a perspective bottom view, illustrating my 20 invention as applied to the folding legs at one end of a bench or table. Fig. 2 is a longitudinal vertical sectional view. Fig. 3 is a transverse vertical sectional view, and Fig. 4 is a perspective view of one of the lock-hinges 25 detached.

The same letters refer to the same parts in all the figures.

A in the drawings designates the leaf or top of a bench or table to which my invention is 30 applied. To the under side of the said leaf or top, near the ends of the same, are secured cross-pieces B B, to which the lock-hinges are applied. These cross-pieces, however, may be dispensed with when desired, their function 35 being merely that of braces.

B' B' are the lock-hinge brackets, which are provided at their upper edges with flanges C, having perforations D, to receive the screws or bolts E, by which the said brackets are 40 fastened to the under sides of the braces B, as shown. The outer edges of the brackets B' have stop-flanges E'. Their inner edges are rounded at the bottom, as shown at F, and their bottom edges have notches G, arranged 45 below and in a vertical line with the vertical slots H, formed in the said brackets.

I I designate the legs, each pair of which

are connected by rounds J and K. The legs are connected to the hinge-brackets by means of screws L, passing through the slots H in 50 the sides of said brackets. The legs are also provided with laterally or outwardly projecting lugs M, adapted, when the legs are unfolded, to enter and rest in the notches G.

N designates a rail secured longitudinally 55 under the table-top, and provided with a laterally-extending lug or stud, O, on which is coiled a spring, P, the extending ends of which rest, respectively, under and against the table-top, as at Q, and against the round K, as at 60 R. The function of this spring is to retain the legs securely in any position to which they may be adjusted, whether folded or extended.

The operation of this invention will be readily understood from the foregoing de- 65 scription, taken in connection with the drawings hereto annexed. The legs, when not in use, will fold under the top of the table or bench. When they are extended for use, the round K will bear against and expand the 70 spring P, which, as soon as the lugs M pass the rounded corners F of the hinge-brackets, serves to lift the legs and force the said lugs M into the notches G of the said brackets, such vertical motion being made possible by the 75 vertical slots H, formed in the said brackets. The legs are thus retained securely in an ex- 80 tended position until it is desired to fold them, when, by simply raising the table-top, and meanwhile pulling the legs in a downward direction, the lugs M may be disengaged from the notches G and the legs be folded.

I claim as my invention and desire to secure by Letters Patent of the United States—

The combination, with the table top and 85 legs, of the herein-described bracket, comprising a plate having fastening-flanges at its upper edge, stop E at the outer edge fitting around one side of the legs, a rounded inner corner, F, at the lower end, a vertical elongated slot, H, in the side, a notch, G, at the 90 bottom edge, a screw, L, passing through the slot H into the legs, and a pin, M, projecting from the legs and arranged to enter the notch

G, a slat, N, arranged under the table-top, a stud, O, extending laterally outward from the same, and a spring, R, coiled around the stud, one arm of the spring bearing against the table-top and the other arm against one of the rungs of the leg, as set forth.

In testimony that I claim the foregoing as

my own I have hereto affixed my signature in presence of two witnesses.

JACOB BENEDICT.
